Patented Aug. 23, 1960

188,677

GOLF CLUB ATTACHMENT

Ingolver T. Thorndon, 1744 Pembrook Road,
Springfield, Ohio

Filed Sept. 29, 1958, Ser. No. 52,799

Term of patent 14 years

(Cl. D34—5)

I claim:

The ornamental design for a golf club attachment, as shown.
